COMBINED BENCH AND TABLE

Ralph Mondragon, Taos, N. Mex.
(P.O. Box 199, Ranchos de Taos, N. Mex. 87571)

Filed Feb. 16, 1973, Ser. No. 346,964

Term of patent 14 years

Int. Cl. D6—01, 03
U.S. Cl. D6—33

FIG. 3

FIG. 5

FIG. 2

FIG. 1

FIG. 4

FIG. 1 is a perspective view of a combined bench and table showing my new design;

FIG. 2 is a front elevational view;

FIG. 3 is a top plan view;

FIG. 4 is a bottom plan view; and

FIG. 5 is a side elevational view.

The side of the combined bench and table not shown is a mirror image of FIG. 5.

I claim:

The ornamental design for a combined bench and table, as shown and described.
